CLAIM

The ornamental design for a quick release mount, as shown and described.

DESCRIPTION

FIG. 1 is a front perspective view of a first embodiment of the quick release mount showing our new design;

FIG. 2 is a front view thereof;

FIG. 3 is a back view thereof;

FIG. 4 is a top view thereof;

FIG. 5 is a bottom view thereof;

FIG. 6 is a left side view thereof, which is a mirror of the right side view;

FIG. 7 is a left side view thereof, shown with environment;

FIG. 8 is a front perspective view of a second embodiment of the quick release mount showing our new design;

FIG. 9 is a front view thereof;

FIG. 10 is a back view thereof;

FIG. 11 is a top view thereof;

FIG. 12 is a bottom view thereof; and,

FIG. 13 is a left side view thereof, which is a mirror of the right side view.

The broken line showing of a quick release mount is for the purpose of illustrating portions of the article and forms no part of the claimed design. The broken line showing of a storage case is for the purpose of illustrating environmental structure and forms no part of the claimed design.
